[57] CLAIM

The ornamental design for a mobile element, as shown and described.

DESCRIPTION

FIG. 1 is a perspective view of a mobile element embodying our new design;

FIG. 2 is a right side elevational view of the mobile element;

FIG. 3 is a top plan view thereof;

FIG. 4 is a front elevational view thereof;

FIG. 5 is a bottom plan view; and

FIG. 6 is an enlarged fragmentary view of a portion of the mobile element.
